[57] CLAIM

The ornamental design for a baseball shoe sole, as
shown and described.

DESCRIPTION

FIG. 1 is a bottom and right front perspective view of
a baseball shoe sole showing my new design;

FIG. 2 is a bottom plan view thereof;

FIG. 3 is a right side elevational view thereof;

FIG. 4 is a rear elevational view thereof;

FIG. 5 is a front elevational view thereof;

FIG. 6 is a cross-sectional view as taken from line 6—6
of FIG. 2;

FIG. 7 is a cross-sectional view as taken from line 7—7
of FIG. 2.
